PANTS HANGER

Mayo E. Leonard, Toledo, Ohio

Application April 23, 1935, Serial No. 17,852

2 Claims. (Cl. 223—95)

The present invention relates to a pants hanger which is designed to hang pants by internal pressure assuring garment to be spread to which without chance of wrinkles or marks caused by 5 clamps or other appliances. And it is almost impossible for the garment to fall off or to be accidentally knocked from the hanger. This hanger is also constructed so that even pressure is exerted on each leg of trouser regardless of 10 errors of tailoring and width.

Another important object of the invention resides in the provision of a device of this nature which is comparatively simple in its construction, inexpensive to manufacture, strong and durable, easy to manipulate and otherwise well adapted to the purpose for which it is designed.

With the above and numerous other objects in view as will appear as the description proceeds, the invention consists in certain novel features 0 of construction, and in the combination and arrangement of parts as will be hereinafter more fully described and claimed.

In the drawings:

Figure 1 is a side elevation of the apparatus embodying the features of my invention showing the same in use.

Figure 2 is an end elevation thereof.

Figure 3 is a side elevation of the apparatus not in use.

Figure 4 is a vertical longitudinal section therethrough.

Figure 5 is a sectional view taken substantially on the line 5—5 of Figure 4.

Figure 6 is a perspective view of one of the pants leg engaging elements.

Figure 7 is an end elevation of the casing.

Figure 8 is a perspective view of a follower.

Figure 9 is a sectional view therethrough.

Figure 10 is an end elevation of another combined follower and pants leg engaging element.

Figure 11 is a sectional view taken substantially on the line 11—11 of Figure 10.

Figure 12 is a top plan view of the modified form of leg engaging elements.

Referring to the drawings in detail it will be seen that numeral 5 denotes an elongated substantially tubular split casing having parallel spaced depending flanges 6—6 and on the ends thereof being provided with caps 7. A cylindrical block 8 is located in the center of the casing and has a hook 9 engaged therewith. Cylindrical follower blocks 10 are mounted in the casing and springs 11—11 are disposed between the block 8 and the blocks 10—10 urging the latter blocks outwardly. These blocks 10—10 are provided with

T-shaped stems 12 depending therefrom between the flanges 6. Pants engaging elements are provided in two pairs. Each clamp engaging element comprises a semi-cylindrical portion 15 merging at one edge into a diametrically outwardly extending extension 16 which in turn merges into an outwardly right angular extension 17 which in turn merges into a depending right angular extension 18 which in turn terminates in a plate 19 the inner edge of which is provided with corrugated teeth 20 and the outer edge, at the upper portion thereof is provided with a notch 21. There are a pair of these elements at each end of the casing with the semi-cylindrical portions 15 in the casing and the remaining portions 18 depending therefrom with the blocks 10 having the head portions of the inverted T-shaped pins 12 engaged in the notches 21 so as to urge the pin engaging elements outwardly.

In Figures 10, 11 and 12 I have shown another embodiment of the invention wherein pins 30 and 31 depend from the follower block 10' and extend through, respectively, openings 32 and arcuate slots 33 provided in the cross plate 34 which connects the depending spaced parallel 25 co-extensive plates 35 together the inner edges of which are provided with corrugations 36.

The operation and utility of this invention seems to be almost self evident from the above 30 description. Obviously the pants engaging elements are pressed inwardly and engaged with the inverted upper end portions of the legs of the trousers to be hung as shown in Figure 1 and hold them in pressed position.

It is thought that the construction, operation, utility and advantages of this invention will now be quite apparent to those skilled in this art without a more detailed description thereof.

Having thus described the invention, what is 40 claimed as new is:

1. In a device of the class described, a casing, trouser engaging devices at the ends of the casing and slidably therein, each device comprising a pair of members having semi-cylindrical portions in the casing merging into downwardly disposed portions which in turn merge into outwardly disposed portions which in turn merge into depending plates the outer edges of which are provided with corrugated teeth and the inner edges of which are provided with notches, followers slidably in the casing between springs and said members and having inverted T-shaped stems the heads of which are engageable in the notches.
2. In a device of the class described, a tubular 55

casing having a longitudinal slot therein defined by depending longitudinally extending spaced flanges, a centrally disposed cylindrical slot in said casing, a coil spring in said casing on each side of said slot and terminating short of the end of said casing, trouser engaging devices slidable in the ends of said casing comprising a pair of members having cylindrical portions in the casing merging into downwardly disposed portions 10 projecting through the slot which in turn merge into outwardly disposed portions which in turn

merge into depending plates, the outer edges of which are provided with corrugated teeth and the inner edges of which are provided with oppositely disposed notches therein, followers disposed between the free end of said spring and the inner end of the trouser engaging devices having inverted T-shaped stems projecting through said slot, the heads of which are engageable in the notches in the trousers engaging devices. 5

10 MAYO E. LEONARD.
